H. E. DAKIN.

CODE LOCKING DEVICE FOR THE STEERING PILLARS OF CYCLES.
APPLICATION FILED DEC. 24, 1920.

1,411,168.

Patented Mar. 28, 1922.

FIG. 1.

FIG. 2.

A technical drawing of a cylindrical component. The component has a central slot labeled 'a' and a ribbed outer edge labeled 'g'. A vertical line labeled 'f' passes through the center of the cylinder. A horizontal line labeled 'd' is at the bottom. A horizontal line labeled 'a' is at the top. A dashed rectangular line labeled 'A' encloses the top and bottom of the cylinder. A small rectangular cutout on the left side is labeled 'a' with a prime symbol.

UNITED STATES PATENT OFFICE.

HERBERT ERNEST DAKIN, OF LONDON, ENGLAND, ASSIGNOR TO HERBERT E. DAKIN
LIMITED, OF LONDON, ENGLAND, A CORPORATION OF GREAT BRITAIN.

CODE LOCKING DEVICE FOR THE STEERING PILLARS OF CYCLES.

1,411,168.

Specification of Letters Patent. Patented Mar. 28, 1922.

Application filed December 24, 1920. Serial No. 433,010.

To all whom it may concern:

Be it known that I, HERBERT ERNEST DAKIN, a subject of the King of Great Britain, and resident of 31-33 High Holborn, 5 London, W. C. 1, England, have invented an Improved Code Locking Device for the Steering Pillars of Cycles, of which the following is a specification.

This invention relates to a code locking device for the steering pillar of a cycle and consists in an improved construction of lock designed to be readily fixed into the steering head of the cycle through which head the bolt of the lock protrudes and engages the 15 steering pillar. A further feature of the invention consists in an improved method of mounting the bolt within the lock so that the bolt cannot be pulled outwardly whilst the code locking rings are turned with the 20 object of "feeling" for the channels in the code rings, thereby ascertaining the combination of letters or numerals forming the code for releasing the bolt.

According to this invention the outer end 25 of the locking bolt is engaged by a rotatable cap in such a manner that rotation of the cap imparts a rectilineal movement to the bolt. The rotatable cap is mounted in a sleeve which contains the bolt and said 30 sleeve is screwed into the steering head, a washer being employed to provide a bearing surface for the adjacent code ring of the lock.

A lock constructed according to this invention is illustrated in the accompanying 35 drawing in which,

Fig. 1 is a longitudinal section, and

Fig. 2 a cross section on line X—X of Fig. 1.

Fig. 3 is a side elevation of the locking device.

The lock consists of a sleeve α formed with a reduced end or plug α' adapted to be screwed into the steering head A of the cycle 45 frame and on this sleeve are rotatably mounted the rings d bearing the numerals or letters of the code. A washer c is employed to provide a bearing surface for the innermost of the concentric rings d , which 50 are rotatably mounted on the sleeve α . The outer end of the sleeve α is formed with a head α^2 forming a fixed index by which the code can be set as hereinafter described.

The interior of the sleeve α is formed to 55 receive the locking tongue or bolt e provided

with projecting pins e' which pass through a groove or guide a^3 formed in the sleeve α and enter the annular groove d' in the rings d . The outer end of the locking bolt 60 e is larger in diameter than the inner end and is formed with a screw-thread which is engaged by a screw cap f mounted rotatably in the end of the sleeve α and held against longitudinal movement by a spring ring f' .

The rings d and the head α^2 of the 65 sleeve α are marked with numerals or letters, from which the code is formed by means of which the steering head is locked or unlocked.

When it is desired to lock the steering 70 pillar B the rings d are adjusted relatively to the fixed head α^2 to form the code. The slots d^3 in the rings will now be in alignment and provide a free passage for the pins e' . Upon the screw cap f being rotated 75 the locking bolt e will be caused to travel longitudinally of the sleeve α , causing the inner end of the bolt e to project beyond the end α' of the sleeve and enter a hole provided in the steering pillar B thus locking 80 same to the head A, as illustrated in Fig. 1 of the drawings. The rings d may now be turned indiscriminately to disturb the code.

In code locks of the type above described 85 the bolt is commonly formed integral with a head whereby the bolt is withdrawn. In such a case if a person desired to ascertain the code for releasing the bolt he pulls the bolt and turns each ring until he feels that the corresponding pin of the bolt is no 90 longer pressed against the ring which indicates the slot a^3 in the ring is opposite to the pin. In this manner he is enabled to arrange the code rings so as to release the bolt. In my improved construction the bolt 95 cannot be pulled outwardly, owing to the interposition of the spring f' between the sleeve and the cap, and therefore a person 100 cannot pull the bolt to ascertain the position of the code rings to release the bolt.

What I claim as my invention and desire 105 to secure by Letters Patent is:—

1. A locking device for the steering pillar of a cycle, comprising a slotted sleeve screw threaded for attachment to the steering pillar of the cycle, code lock rings mounted on said sleeve, a locking bolt screw threaded at its outer end and carrying pins sliding in said slot in the sleeve and controlled by said code lock rings, a washer interposed between 110

the said code lock rings and the steering pillar and forming a bearing surface for the innermost code locking rings, a rotatable cap provided with a screw threaded recess on 5 its inner face engaging with the screw threaded outer end of the said locking bolt, and means for holding the said rotatable cap against longitudinal movement, whereby 10 rotation of said cap screws the locking bolt back and forth in said sleeve, substantially as described.

2. In a lock for the steering pillar of a cycle, the combination of a sleeve attachable to the steering head of a cycle, a screw

threaded bolt sliding in said sleeve, a rotatable cap mounted on the outer end of said sleeve and having a screw threaded recess engaging said bolt and whereby said bolt may be screwed back and forth in said sleeve, 15 said sleeve and rotatable cap having grooves 20 in their adjacent faces, a spring locking ring lying in said grooves in the sleeve and rotatable cap, to hold the latter against longitudinal movement, and code controlled means mounted on said sleeve for controlling said 25 screwed bolt, substantially as described.

HERBERT ERNEST DAKIN.
